UNITED STATES PATENT OFFICE

93,410

DESIGN FOR AN ICE CREAM CONE

Thomas H. Keller, Cincinnati, Ohio, assignor to
Lanier Cone Company, Cincinnati, Ohio, a cor-
poration of Ohio

Application May 3, 1934, Serial No. 51,678

Term of patent 14 years

To all whom it may concern:

Be it known that I, THOMAS H. KELLER, a citizen of the United States, residing in the city of Cincinnati, in the county of Hamilton and State of Ohio, have invented a new, original, and ornamental Design for an Ice Cream Cone, for which the following is a specification, reference being had to the accompanying drawing, forming part thereof.

In the drawing:

Figure 1 is a front perspective view of an ice cream cone showing my design.

Figure 2 is a rear perspective view of the same.

Figure 3 is a side perspective view of the same.

I claim:

The ornamental design for an ice cream cone, as shown.

THOMAS H. KELLER.
